UNITED STATES PATENT OFFICE.

CHARLES F. PIKE, OF PHILADELPHIA, PENNSYLVANIA, ASSIGNOR TO THE NATIONAL ANTI-SEWER GAS COMPANY, OF CAMDEN, NEW JERSEY.

WATER-CLOSET.

SPECIFICATION forming part of Letters Patent No. 270,981, dated January 23, 1883.

Application filed August 7, 1882. (No model.)

To all whom it may concern:

Be it known that I, CHARLES F. PIKE, a citizen of the United States, residing at Philadelphia, in the county of Philadelphia and State of Pennsylvania, have invented certain new and useful Improvements in Water-Closets, of which the following is a specification, reference being had therein to the accompanying drawings, wherein—

10 Figure 1 is an elevation, partly sectional, on line 2 2, Fig. 2, of a water-closet embodying my invention. Fig. 2 is a section on line 1 1, Fig. 1. Fig. 3 is an enlarged sectional view of pull and push rod mechanism. Fig. 4 is a broken 15 section of a modification of same. Fig. 5 is a section on line 3 3, Fig. 4. Fig. 6 is an elevation of modified form of valve; and Figs. 7 and 8 are sections on the lines 4 4 and 5 5, respectively, of Fig. 3.

20 My invention has relation to water-closets, and has for its object to so construct such devices that sewer-gas or fecal-matter odor cannot escape therefrom.

My invention accordingly consists of a water-25 closet having a bowl and a container in which a pocket or chamber is formed of such dimensions that the pull-rod and operating mechanism for the clapper or pan are received therein. To said container is secured the water-cock, designed to be opened and closed from 30 within the container, all drip or waste water from the cock passing directly therefrom into the container. The opening in the latter through which the pull-rod passes is sealed by 35 means of a rubber or flexible packing or valve.

Referring to the accompanying drawings, A represents a water-closet bowl sealed at a on the container B. The latter is formed with a pocket or chamber, b, as plainly shown in Fig. 2.

40 C represents the pan or clapper for the bowl, hinged at c c to the container-lid B', and is provided with a segmental gear, c', which meshes with a like gear, d, pivoted at d' to container-partition b', and has an arm or lever, d', provided with a pin, d'', entering a slot, e, in the pull and push rod E. The latter extends up through a tube, F, depending from a projection, B'', on lid B', as shown. On the lower end of tube F is a flange, f, and f' 45 is a rubber ring or gasket seated thereon. Surrounding said tube is a disk, g, forming the

top of a cylinder, G, secured to or formed on rod E. Said disk seats itself on rubber ring f', and forms a valve for sealing the tube F, so that no sewer-gas or fecal-matter odor in the 55 container can pass out thereof or escape therefrom.

H represents the water cock, of any suitable construction. h is the supply-pipe therefor, and h' the flushing-pipe for the bowl.

It will be noticed that the cock H is secured to the side of the container, so that the push-rod h³ for its valve projects into the container, as shown, and is operated by the side d³ of gear d.

The operation of the foregoing-described parts is as follows: The closet having been used, the rod E is elevated. As it rises the disk g leaves rubber f' and assumes the position shown in dotted lines x, Fig. 1. The arm d' is also raised, rotating gears d and c' to lower the clapper or pan C. At the same time the edge d³ of gear d pushes in rod h³ of the cock H, opening the latter, and the bowl is flushed. All water and fecal matter therein drop into 70 chamber B³ of the container, and pass from thence to the usual P or S trap and soil-pipe. When rod E is depressed the movements of said parts are reversed, the disk g seats itself on rubber f', the pan or clapper C is returned 80 to its normal position, and the cock H is permitted to close.

It will be seen that the container is made air-tight and no sewer-gas or odors can escape therefrom.

The chamber b' is so located, as is plainly seen in Fig. 2, that nothing dropping out of the bowl will fall thereinto. Consequently the mechanism contained therein is preserved from all contact with fecal matter or water.

In Fig. 4 I have shown the rubber ring f' placed in a recess in the lid B' and the cylinder G placed on the rod E exterior to the container, its lower edge resting or seating upon the rubber ring f'; or, if desired, an ordinary valve, L, may be formed on rod E as a substitute for disk g and seat f f'. The cylinder G (shown in Fig. 1) may be filled with water or mercury, preferably the latter, or a running stream of water, in order that when 95 rod E is raised the end f of tube F will still be sealed.

The seal for bowl A (shown in Fig. 2) may be the usual water seal, or a running-water or a disinfectant-water seal may be used therefor, as fully shown and described in applications 5 made by me of even date herewith.

I have shown the application of the sealed push-rod E to water-closets provided with containers made separate from the bowls; but it is apparent that such rod may be employed on 10 that class of closets wherein the bowls and containers are made in one piece and provided with plug-valves in lieu of the pans or clappers.

What I claim as my invention is—

1. The combination, with a water-closet bowl, 15 of a container, B, having partitions b' and chambers b B^3 , the chamber b containing the push-rod, a seal therefor, and mechanism for operating the pan or clapper of the bowl, substantially as shown and described.
2. In combination with a water-closet bowl, 20 a pan or clapper, a container, B, having partition b' and chambers b B^3 , the chamber b containing the push-rod E, a seal therefor, and operating mechanism for the pan or clapper, 25 which also moves the stem of the water-cock projecting into said chamber, substantially as shown and described.
3. The combination of container B, lid B' , 30 provided with projection B^2 and depending-tube F, flanged at f, the rubber ring f' , and rod E, having cylinder G, with head g, substantially as shown and described.
4. The combination, with tube F, secured to

lid or frame B' , having flange f and rubber ring f' , of rod E, provided with cylinder G and head g, substantially as shown and described. 35

5. The combination of bowl A, having pan or clapper C, the container B, having chambers b B^3 , the lid B' , the push-rod E, provided with means for sealing the opening in the lid 40 through which it passes, and mechanism interposed between said rod and the pan or clapper for operating the latter, substantially as used for the purposes set forth.

6. The combination of bowl A, pan or clapper 45 C, container B, composed of chambers b B^3 , lid B' , push-rod E, having slot e, and provided with means for sealing the bearing through which it passes, and mechanism interposed between said rod and pan or clapper 50 and between the stem of the water-cock for operating said pan and clapper, substantially as shown and described.

7. The combination, with a water-closet, of a 55 push-rod provided with a flange which seats upon a packing, substantially as shown and described, for sealing said rod at the upper opening or bearing through which it passes, substantially as set forth.

In testimony whereof I affix my signature in 60 presence of two witnesses.

CHARLES F. PIKE.
